UNITED STATES PATENT OFFICE.

JAMES SWAN, OF SEYMOUR, CONNECTICUT.

DESIGN FOR A TOOL-HANDLE.

SPECIFICATION forming part of Design No. 27,301, dated July 6, 1897.

Application filed May 24, 1897. Serial No. 637,966. Term of patent 14 years.

To all whom it may concern:

Be it known that I, JAMES SWAN, a citizen of the United States, residing at Seymour, in the county of New Haven and State of Connecticut, have invented and produced a new and original Design for Tool-Handles; and I do hereby declare the following to be a full, clear, and exact description of the same, reference being had to the accompanying drawing, forming a part thereof, in which the figure represents a side elevation of a tool-handle embodying my design.

The leading feature of my design consists in a tool-handle having the surface of its gripping portion provided with rounded ribs parallel with each other and with the axis of the handle, the spaces between said ribs being open at the ends, imparting to said gripping portion the appearance of a fluted roll. The end of the handle is rounded, as at 1, and adjacent to said end is the gripping por-

tion 2, below which the configuration of the handle and its usual metal ferrule may be of the usual or any preferred form.

The surface of the gripping portion is ornamented by a series of straight parallel rounded ribs *a*, with spaces *b* between said ribs, the whole imparting to said gripping portion the appearance of a fluted roll, and ribs alternating with spaces or grooves which 25 are open at the ends where the rounded portion 1 and a lower reduced portion meet the gripping portion.

What I claim is—

The design for a tool-handle substantially 35 as shown and described.

In testimony whereof I affix my signature in presence of two witnesses.

JAMES SWAN.
